ATTORNEY

UNITED STATES PATENT OFFICE.

LUKE SHEA SLOANE, OF OKMULGEE, OKLAHOMA.

WRENCH.

1,406,293.

Specification of Letters Patent. Patented Feb. 14, 1922.

Application filed June 18, 1921. Serial No. 478,643.

To all whom it may concern:

Be it known that I, LUKE S. SLOANE, a citizen of the United States, residing at Okmulgee, in the county of Okmulgee and 5 State of Oklahoma, have invented new and useful Improvements in Wrenches, of which the following is a specification.

My present invention has reference to wrenches.

10 My object is to produce a pipe wrench which may be quickly adjusted to engage an object between the jaws thereof and which shall be of such construction that a binding between the jaws of the wrench and the object 15 acted upon will not occur when the wrench is turned to take a fresh hold on the object.

The foregoing, and other objects which will appear as the nature of the invention is 20 better understood, may be accomplished by a construction, combination and operative association of parts, such as is disclosed by the drawings which accompany and which form part of this specification.

25 In the drawings:—

Figure 1 is a perspective view of a wrench in accordance with this invention.

Figure 2 is a sectional view on the line 2—2 of Figure 1.

30 Figure 3 is a sectional view on the line 3—3 of Figure 1.

Figure 4 is a sectional view on the line 4—4 of Figure 1.

As disclosed by the drawings, my improved wrench comprises essentially two members, each of which having a shank, one of the shanks is indicated by the numeral 1 and the other by the numeral 2. The shanks, are arranged one over the other, and 40 have their confronting edges toothed, as at 3 and 4 respectively. The teeth 3 of the shank 1 are designed to be received between the teeth 4 of the shank 2. The shank 2 is of a materially greater length than the shank 1 and has one of its ends provided with a handle 5 and its other end with a head 6. One end of the shank 1 is provided with an angle head 7 which is disposed 45 opposite the head 6. The inner face of the head 7 is straight, but is toothed or serrated to provide a gripping jaw 8. The outer face of the head 6 is disposed at an angle as indicated by the numeral 9. The angle end 7, of the head 6, is, at a distance below the 50 portion thereof formed with the shank 2 centrally provided with a depression form-

ing a pocket 10, the said pocket having its side walls provided with inwardly directed ribs 11 and its rear wall 12 arranged at the same inclination as the face or end 9. The 60 head 6, adjacent to the outer end thereof is provided with a threaded opening 13, which enters from its rear and communicates with the pocket 10. In this threaded opening there is a set screw 14 that has the end 65 thereof that enters the pocket of a conical formation, as indicated by the numeral 15.

Arranged for slideable movement over the angle face 9 of the head 6 is a toothed or serrated jaw 16. The jaw is centrally provided on its inner face with a web flange 17, whose sides are provided with longitudinal depressions 18 to receive the ribs in the pocket. The inner end of the web rests against the inner angle wall 12 of the 75 pocket, and the upper wall of the pocket has a depression 19 therein which forms a seat for a comparatively light helical spring 20 that exerts a pressure against the upper end of the web of the jaw 16. The web of the 80

jaw 16 has its lower or inner face cut away from the end thereof, the upper wall formed by the said cut-away portion forming a rounded shoulder 21 that is engaged by the conical end 15 of the screw 14. The spring 85 20 forces the movable jaw 16 outwardly of the head 6 and into contact with the set screw. When the wrench is arranged to receive an object between the jaws thereof the jaw 16 will be moved inwardly against 90 the pressure of its spring which is especially true when pressure is applied on the handle of the wrench to turn the object. When such pressure is released, the spring will be free to exert its pressure against the jaw 16 95 to force the same outwardly of the head 6, and consequently prevent binding on the object by the heads. Thus the wrench may easily ratchet over the object engaged.

On the edges of the shank 2, directly inward of the head 6 thereof there are spaced ears 22 which contact with the sides of the shank 1. Also on the shank 1 there is a substantially U-shaped stirrup member 23. The member 23 is preferably removably secured 105 to the shank 2, by the means 24. The side members of the yoke project a suitable distance beyond the outer edge of the shank 1 and have pivoted therebetween, as at 25 a lever 26. The lever, opposite its pivot has 110 a cam projection 27 whereby, when the lever is swung to one position, to bear on the outer

edge of the shank 1, and move the said shank bodily to bring the teeth 3 thereof into engagement between the teeth 4 of the shank 2. Thus the sections comprising the wrench 5 may be easily and quickly adjusted.

Having described the invention, I claim:--

In a wrench construction, as herein described, co-operating heads having angle shanks disposed in lapping relation and having their confronting faces for the major length thereof provided with coengaging teeth, ears on the sides of one of the shanks

adjacent to the head thereof frictionally engaging the sides of the other shank but not projecting therebeyond, a yoke surrounding 15 the first mentioned shank, secured thereto and having its parallel arms arranged against the sides of the second shank and projecting therebeyond, and a cam lever pivoted between said arms at the outer ends 20 thereof for engagement with the outer surface of the second mentioned shank.

In testimony whereof I affix my signature.

LUKE SHEA SLOANE.
